UNITED STATES PATENT OFFICE.

HORACE B. PHILLIPS, OF FAIRMONT, NORTH CAROLINA.

STILL.

1,076,389.

Specification of Letters Patent.

Patented Oct. 21, 1913.

Application filed March 8, 1913. Serial No. 752,907.

To all whom it may concern:

Be it known that I, HORACE B. PHILLIPS, a citizen of the United States, and a resident of Fairmont, in the county of Robeson and 5 State of North Carolina, have made certain new and useful Improvements in Stills, of which the following is a specification.

My invention relates to improvements in stills, more especially those stills used for the 10 production of turpentine, and it consists in the combinations, constructions, and arrangements herein described and claimed.

An object of my invention is to provide a device in which pine wood containing tur- 15 pentine may be treated without any danger of overheating the wood.

A further object of my invention is to provide a device of a portable nature which may be readily set up in one section and 20 moved to another.

A further object of my invention is to provide a device having a furnace so constructed and located that much of the heat which would be otherwise wasted is saved.

25 A further object of my invention is to provide a device in which the wood may be more readily led into and discharged from stills of the ordinary type.

Other objects and advantages will appear 30 in the following specification and the novel features of the device will be particularly pointed out in the appended claims.

My invention is illustrated in the accom- 35 panying drawings forming part of this specification in which—

Figure 1 is a front view of the still, Fig. 2 is an enlarged sectional view, Fig. 3 is a section along the line 3—3 of Fig. 2, Fig. 4 is a section along the line 4—4 of Fig. 2, 40 and Fig. 5 is a diagrammatical view showing the oil pipe connections.

In carrying out my invention I provide a base 1 of rectangular box-like shape. This may be carried by a foundation 2 of any 45 suitable construction. Mounted upon the base is a series of coils of pipe 3. As will be seen from Fig. 2, these coils are arranged vertically and adjacent coils are connected by short connections 3^k. The spaces between 50 the adjacent rows of vertical coils are designed to be filled with the wood 4 in the manner shown in Fig. 1.

Arranged to fit over the base portion 1 is a cover portion 5. This cover portion may 55 be raised or lowered in any suitable manner such as by power devices (not shown) at-

tached to the cables 6. The cover portion 5 bears the furnace. The latter consists of a casing 6 provided with grate bars 7, a door 8 in the wall of the top portion 5, and a chimney or stack 9. On the inside of the furnace preferably along the walls and top thereof are arranged coils of pipe 10. The two ends of the pipe coils 10 extend through the wall of the cover portion 5 terminating 65 on the outside thereof as shown at 10^x and 10^y respectively in Fig. 3. The ends 3^x and 3^y of the coils 3 extend through the base member and terminate on the outside there- 70 of. The terminal portions 3^x and 10^x are connected by means of a pipe 11. The terminal 10^y is connected by a pipe 12 to a pump 13, and the latter is connected to the pipe terminal 3^y by the pipe section 14 (see Fig. 1). 75

From the foregoing description of the various parts of the device the operation thereof may be readily understood. The apparatus is set up as shown and the furnace is filled with combustible material. The pipes 80 3 and 10 are designed to be filled with the oil or other suitable liquid. The heat from the furnace will cause the oil to become heated and it may then be pumped through pipes 3 and 10 by means of the pump 13. 85 The coils 3 form not only heating members, but also racks for supporting the wood. The circulation of the oil provides a heating medium which is sufficient to drive off the turpentine which may be led out through the 90 pipe 15 to a condenser (not shown). As the turpentine distils the tarry matter gathers in the bottom of the base 1 and may be drained off at the cock 16.

When the process is finished the connect- 95 ing pipes 10, 12 and 13 may be unscrewed and taken off and the cover may be lifted from the base by any suitable power means. The wood may then be removed directly from the racks formed by the coils 3 and the 100 charge may be placed in. The cover may then be lowered and the pipes 11, 12 and 14 may again be secured in place and the operation repeated.

It will be seen from the above construc- 105 tion that very little heat is wasted in the process. As fast as the oil is heated it is pumped out of the interior of the furnace into the heating coil 3. The furnace being on the inside of the device utilizes any heat 110 which might escape from the walls of the furnace were the latter outside of the casing

formed by the base 1 and the top 5. The pump may be run by any suitable motor and is designed to run at such speed as to permit the proper circulation within the pipes.

5 I claim:

1. In a still, a base portion comprising a rectangular box, a series of heating coils spaced apart to provide racks for the material to be treated, a cover for said base portion, a furnace carried by said cover, and means for heating the coils from the furnace.

10 2. In a still, a base portion comprising a rectangular box, a series of heating coils spaced apart to provide racks for the material to be treated, a cover for said base portion, a furnace carried by said cover, means for heating the coils from the furnace, said means comprising a series of coils within the furnace, and connections between the coils 15 of the furnace and the rack coils.

20 3. In a still, a base portion, a series of coils carried thereby, said coils being spaced apart to provide room for the material to be treated, a cover for said base portion, and a furnace carried by said cover on the inside 25 thereof.

4. In a still, a base portion, a series of coils carried thereby, said coils being spaced apart to provide room for the material to be treated, a cover for said base portion, a furnace carried by said cover on the inside 30 thereof, means for carrying off the products of distillation, and means connected with said base portion for draining the latter of the liquid products of distillation.

35 5. In a still, a rectangular box-like base portion, a series of rows of vertically extending coils, said rows being spaced apart to form racks for the material to be treated, a box-like cover arranged to surmount said 40 base portion, a furnace carried within said cover, pipes disposed within the interior of said furnace, said coils and said pipes being arranged to receive a circulating fluid, connections between the pipes and said coils, 45 and a pump for circulating the fluid in said pipes and said coils.

HORACE B. PHILLIPS.
